[57] CLAIM

The ornamental design for a food product assembly table, substantially as shown and described.

DESCRIPTION

FIG. 1 is a front perspective view of a food product assembly table showing our new design;

FIG. 2 is a front elevational view thereof;

FIG. 3 is a top plan view thereof;

FIG. 4 is a left side elevational view thereof, showing the counter in the horizontal raised position;

FIG. 5 is a right side elevational view thereof, showing the counter in a lowered position; and

FIG. 6 is a rear elevational view thereof.

FIG. 1

FIG. 2

FIG. 3

FIG. 4

FIG. 5

FIG. 6
